ANTIRAVEL WELT JUNCTURE FOR STOCKINGS

Application filed July 22, 1930. Serial No. 469,667.

This invention relates to anti-ravel welt junctures for knitted articles such as stockings, as well as to methods of forming such junctures.

Heretofore anti-ravel welt junctures for stockings had to be formed entirely by hand through lateral displacement of loops of the initial course of the knitting by manipulation of the transfer bar and as an incident to closing of the welt upon the needles of the producing machine. This operation was extremely tedious particularly in connection with fine gage work and therefore required the employment of skilled knitters, consumed considerable time in its performance, and added materially to the cost of production of the stockings.

The chief aim of my invention is to overcome the above recited drawbacks of previous practice by making possible the formation of anti-ravel welt junctures upon full fashioned knitting machines without increase in the cost of production of the stockings. This desideratum I secure, as hereinafter fully set forth, by employment of the picot or lock stitch attachment with which most modern full fashioned hosiery knitting machines are equipped, after closure of the welt in the ordinary way, and causing the machine to perform a narrowing cycle, and thereby effect lateral transfer of one of the doubled loops from alternate needles of the machine to the adjacent needles by the points of said picot or lock stitch attachment, and interlooping of such transferred loops with the doubled loops on said adjacent needles to form the anti-ravel barrier.

A further object of my invention is to predetermine as the result of an automatic operation of a stocking knitting machine, an anti-ravel welt juncture which is neat and regular in appearance, inconspicuous and absolutely effective against the continuation of runs, originating in the garter top of a stocking, down through the leg or body portion.

In the drawings, Fig. I is a view of a full fashioned ladies stocking with my novel anti-ravel juncture conventionally indicated.

Fig. II is a diagrammatic sectional view

through the welt of the stocking showing the location of the juncture.

Fig. III is a diagrammatic fragmentary view on a larger scale showing the manner in which fabric loops are taken from alternate needles of the machine by the points of the picot or lock stitch attachment. 55

Fig. IV is a view similar to Fig. III showing how the loops taken as aforesaid by the points of the picot or lock stitch attachment, 60 are transferred to adjacent needles of the machine to form the anti-ravel juncture.

Figs. V, VI, VII and VIII are diagrammatic views showing the manner in which the needles, knockovers and sinkers of the machine and the points of the picot or lock stitch attachment cooperate in forming the anti-ravel welt juncture. 65

Fig. IX is a fragmentary view showing the needle bar of the machine and the point bar 70 of the picot or lock stitch attachment, and further illustrating the manner of cooperation between these parts to form the anti-ravel juncture; and

Fig. X is a diagrammatic fragmentary view showing the character of my novel anti-ravel welt juncture. 75

The stocking delineated in Figs. I and II has its welt W joined to the leg or body portion B by my improved anti-ravel juncture 80 which is conventionally indicated in these figures at 10. The character of the welt juncture is shown diagrammatically in Fig. X wherein the numerals 11 and 12 designate the interlooped terminal courses of the welt. 85 The course 11 is stippled for the purposes of distinction and constitutes the last knit course of the welt fabric; while the course 12 constitutes the first knit course of said welt fabric. As shown, each alternate loop 11a of the last knit course 11 of the welt fabric is crossed with the corresponding loop 12a of the first knit course 12, and, moreover, interlooped with the adjacently allocated doubled loops 11b, 12b of the two welt juncture courses 11, 90 12. Obviously, by such crossing and interlooping of alternate loops of one of the terminal courses of the welt fabric with the intervening doubled loops of the two terminal courses at the line of juncture results 95 100

in an effective barrier to prevent runs originating in the welt or garter top from running down into the leg or body portion of the stocking.

- 5 A welt juncture having the characteristics just described may, in accordance with my invention, be readily made on a full fashioned hosiery machine equipped with a picot or lock stitch attachment, i. e., an attachment which 10 includes, as shown in Fig. IX, a longitudinally-shiftable bar A having points P to correspond with alternate needles of a series N of the knitting machine.

The method of procedure in forming a 15 stocking welt with my improved anti-ravel juncture is as follows: The stocking is started by knitting the first course 12 loose as ordinarily; and a sufficient length of fabric thereafter knit for the welt W whereof the last or 20 terminal course 11 is preferably knit loose like the first course 12. The machine is then set for narrowing by shifting of the cam shaft in the known way; and the fabric is then folded to close the welt by individually engaging the loops 11a of the last knit course 25 11 of the welt fabric over the needles N of the machine through manipulation of the welt bar—likewise in the known manner. However, instead of pressing the newly impaled loops 11a of the course 11 down along the shanks of the needles and onto the noses of the sinkers S of the machine as ordinarily, I 30 keep them up in the tops of said needles as shown in Fig. V. The machine is then started to perform a narrowing cycle with 35 incidental forward movement of the sinkers S under influence of the catch bar of the machine, and descent of the bar A to bring its points P to the level of the beards of alternate needles of the series N, as shown in 40 Fig. VI, while the sinkers gradually recede. In this connection it is to be noted that the loops 12a of the terminal course 12 of the welt uppermost on the needles is supported on 45 the top nibs of the sinkers S until the points P have penetrated the loops 11a of the terminal course 11 lowermost on the needles and resting upon the knock-overs K. As the sinkers S continue to recede, the upper layer 50 of the welt is pulled down by the needles N until it rests upon the knock-overs K as shown in Fig. VII. After completing the dip, the needle points P rise to the positions shown in Figs. VIII and IX with the result that the 55 loops 11a are drawn over the loops 12a. Then, with lateral shifting of the point bar A in the direction indicated by the arrow in Fig. IX, the loops 11a are transferred laterally to a position immediately above the tops 60 of the adjacent needles of the series N and finally engaged with said needles as the narrowing cycle is completed.

Thus through employment of the picot or lock stitch attachment of a full fashioned knitting machine after turning of the welt,

it is possible to form an effective anti-ravel juncture automatically without adding to the cost of production of the stockings. A juncture so made is devoid of irregularities, and, although inconspicuous, distinguished by a 70 neat and attractive appearance.

Having thus described my invention, I claim:

1. The method of forming a ravel proof stocking welt juncture by drawing alternate 75 terminal loops of one thickness of the welt fabric, after folding, over the corresponding terminal loops of the other thickness of the welt fabric; and then transferring the loops 80 so drawn laterally and interlooping them with adjacent doubled terminal loops of the superposed welt layers.

2. The method of forming a ravel proof stocking welt juncture by drawing alternate 85 loops of the last knitted course of the welt fabric over the corresponding loops of the first knitted course of the welt fabric after welt closure; and then laterally transferring the loops so drawn and interlooping them 90 with the adjacent superposed loops of the said first and last knitted courses of the welt.

3. The method of forming a ravel proof welt juncture in stockings upon a hosiery knitting machine; by drawing the nethermost 95 loops on alternate needles of the machine, after welt closure, over the uppermost loops on said needles; and then transferring the loops so drawn laterally to adjacent needles.

4. The method of forming a ravel proof welt juncture in stockings upon a flat hosiery 100 knitting machine equipped with a picot or lock stitch attachment, by drawing the nethermost loops on alternate needles of the machine, after welt closure, by means of the 105 points of said picot or lock stitch attachment, through the uppermost loops on said alternate needles; and then laterally transferring the loops so drawn to adjacent needles through shifting of the points of said picot or lock stitch attachment.

5. The method of forming a ravel proof welt juncture in stockings upon a flat full fashioned hosiery knitting machine equipped with a picot or lock stitch attachment, by 115 setting the machine for narrowing at the completion of the welt fabric; then closing the welt by transfer of the loops of the first knit course on the welt bar to the needles of the machine, but keeping such loops in the tops of the needle; and then causing the machine 120 to perform a narrowing cycle with attendant drawing of the nethermost loops or the loops of the last knit course of the welt fabric on alternate needles, over the uppermost loops or the loops of the first knit course of the welt 125 fabric on such alternate needles, by the points of the picot or lock stitch attachment, and transfer of the loops so drawn to adjacent needles through lateral shifting of the picot points.

6. A stocking with a ravel proof welt juncture wherein alternate loops of one of the terminal courses of the welt fabric are crossed with the corresponding loops of the other terminal course of the welt fabric, and inter-looped with the adjacent doubled loops of the superposed terminal courses along the welt juncture.

In testimony whereof, I have hereunto signed my name at Philadelphia, Pennsylvania, this 18th day of July, 1930.

GEORGE W. GOETSCH.
